UNITED STATES PATENT OFFICE.

SIGURD ELLINGSEN, OF NORTH VANCOUVER, BRITISH COLUMBIA, CANADA.

JACK.

Application filed August 16, 1919. Serial No. 318,022.

To all whom it may concern:

Be it known that I, SIGURD ELLINGSEN, a subject of the King of Norway, residing at North Vancouver, British Columbia, in the county of Vancouver and Dominion of Canada, have invented new and useful Improvements in Jacks, of which the following is a specification.

This invention relates to improvements in lifting jacks and has special relation to jacks used in logging.

An object of the present invention is to provide a jack for this purpose in which the lifting power is materially increased through a novel form of ratchet mechanism, which is so arranged as to permit of a wide range of movement, the lever being capable of movement a distance of approximately ninety degrees, or from a vertical to a horizontal position.

Another object of the invention is the provision of a jack in which the casing is of integral formation to provide strength and durability, the construction being such, however, as to permit of a ready removal of the working parts of the jack, when necessary or desired.

A further object is the provision of a jack casing in which the lifting elements and the operating elements or ratchet mechanism are contained in separate chambers formed within the casing and divided by a partition to define guide walls for both the lifting and operating elements.

Other objects and advantages of the invention will appear as the following description is read in connection with the accompanying drawings.

In the drawings:

Figure 1 is a side elevation of a jack embodying the present invention.

Figure 2 is a front elevation of the same.

Figure 3 is a plan view.

Figure 4 is a vertical sectional view on the line 4-4 of Figure 2.

Figure 5 is a similar view on the line 5-5 of Figure 2.

Figure 6 is a horizontal sectional view on the line 6-6 of Figure 2.

Figure 7 is a detail view of the clevis.

Referring to the drawings in detail, wherein like characters of reference denote corresponding parts, the jack is shown as made up of a casing designated generally at 10 and which is mounted upon a support-

ing base 11, the latter having depending flanges 12 and being removably secured to the casing through the medium of bolts or screws 13, which pass through openings provided in the said base and in the lower end 60 of the casing 10.

The casing is of integral formation and is divided into separate chambers 14 and 15, the former extending throughout the length of the casing and being adapted to receive 65 the lifting element, to be hereinafter described, while the chamber 15 is positioned to one side of the chamber 14, and extends only for a portion of the length of the casing the two chambers being divided by a 70 wall 16. The walls of both the chambers 14 and 15 are provided with aligned openings for the passage of a shaft 17, the ends of the shaft passing through openings 18 in the outer walls of each of the chambers 75 and being received within bearing caps 19, removably secured to the said outer walls through the medium of screws or bolts 20.

Mounted for movement within the chamber 14, is a rack bar 21, one rear side 80 of which is provided with teeth 22, which engage teeth 23, formed on or secured to the shaft 17 intermediate its end, so that a rotation of the shaft, by means to be later described, will move the bar longitudinally 85 of the chamber. The lower end of the bar is provided with a projecting toe 24, which operates within a slot 25 provided in front of the casing, while the upper end of the said bar has removably secured thereon a 90 grip nut 26, thus enabling either end of the bar 21 to be used for lifting and adapting the jack for use in a wide variety of places.

Mounted upon the shaft 17 within the chamber 15, is a ratchet wheel 28, the hub 95 of the said wheel being provided with a hexagonal socket 29, for engagement with a similarly shaped enlargement 30, provided upon the shaft 17 to one side of the teeth 23. This permits the ready removal or 100 positioning of the ratchet wheel upon the shaft, by simply sliding the latter transversely of the wheel.

Mounted upon the shaft 17, and operating over the ratchet wheel 28, is a clevis 31, 105 which comprises spaced plates connected together at one end by means of a web 32. Each of these plates is provided with an opening, the latter being concentrically arranged with respect to one another and of 110

different diameters, the opening 33 in one plate embracing the shaft 17, while the opening 34 in the opposite plate embraces an annular enlargement 35, formed on the said shaft between the hexagonal enlargement 30 and the teeth 23. Mounted between the plates of the clevis 31, upon a pivot pin 36, is a dog 37, which is adapted to engage teeth of the ratchet wheel 28, and 10 is provided with a finger piece 38, which projects beyond the clevis. The dog 37 is normally pressed into engagement with the teeth of the ratchet wheel through the medium of a spring 39, which is secured 15 to the clevis.

Pivotedly mounted between ears 40, provided on the casing 10, as indicated at 41, is an operating handle 42, the latter being bifurcated, as shown, and receiving within 20 such bifurcation one end of a link 43, a pivot pin 44 serving to connect the link with the operating handle. The opposite end of this link is pivotally mounted upon a pin 45, between ears 46, formed in each 25 of the plates of the clevis 31. This provides a wide range of movement for the handle 42 and affords increased leverage for the operation of the jack.

To prevent retrograde movement of the 30 ratchet wheel 28, there is pivotally mounted within the chamber 15, upon a pin 47, a dog 48, which is urged into engagement with the teeth of the ratchet wheel through the medium of a spring 49, carried by the dog. 35 The latter is also provided with a finger piece 50, which projects without the chamber 15.

It is believed that when the foregoing

description is read in connection with the accompanying drawings, the construction, 40 operation and advantages of the invention will be apparent. The right is reserved to make such changes in the form, proportions and minor details of construction as 45 properly fall within the scope of the appended claim.

Having described the invention, what is claimed is:

A jack comprising a casing divided into separate chambers, a toothed lifting element 50 mounted for reciprocation in one of said chambers, a shaft mounted for rotation in the other chamber, teeth carried by the shaft intermediate its ends for operative association with the teeth in the lifting element, a ratchet wheel surrounding the shaft and secured thereto adjacent the teeth thereon and being arranged in the last mentioned chamber, a clevis including spaced plates arranged on opposite sides of the ratchet 55 wheel and each being provided with an opening of a different diameter, said openings being adapted to fit shoulders of like diameters on the shaft and being concentrically arranged with respect to one another, a web connecting the plates adjacent the upper ends, a handle pivotally associated with the wall forming the respective chambers, means pivotally associating the pivoted end of the handle with the clevis and 60 manually operated dogs fixed to the wall and clevis respectively and being associated with the ratchet wheel as and for the purpose specified.

In testimony whereof I affix my signature. 75
SIGURD ELLINGSEN.
